UNITED STATES PATENT OFFICE

2,437,475

METHOD OF MITIGATING CORROSION IN
WELLS

William F. Oxford, Jr., Beaumont, Tex., assignor
to Sun Oil Company, Philadelphia, Pa., a cor-
poration of New Jersey

Application December 5, 1945, Serial No. 632,862

3 Claims. (Cl. 252—8.55)

1

This invention relates to petroleum production and particularly has to do with the prevention or mitigation of corrosion in oil and gas wells.

The completion of a well for the production of petroleum hydrocarbons generally comprises setting a casing in the borehole, inserting a string of tubing within the casing and, after the well has been flushed with water, placing a packer in the annulus between the casing and tubing to close off the upper part of the casing so as not to subject it to the pressure of the productive zone. The casing often is placed through the productive zone and the bottom of the casing is sealed off by means of cement, the well then being opened up for production by gun perforation of the casing adjacent the oil stratum. The well is then permitted to produce through the tubing.

It has been found that in certain cases the well tubing is subjected to corrosion due to corrosive constituents that are carried in the hydrocarbon flow stream. While this is not so often the case in wells producing crude oil, it has been found to be particularly true in high pressure gas-distillate wells wherein the main part of the hydrocarbon flow is in the vapor phase. The hydrocarbon vapors carry along appreciable amounts of water which in the lower portion of the well may be entirely in vapor form due to the higher prevailing temperatures or the water may be present as finely divided liquid particles especially in the upper part of the well where the temperatures are lower. Corrosion in gas-distillate wells has been noted to occur especially severely in the upper portion of the wells (as also in the well fittings and flow lines), perhaps being coextensive with the zone wherein the temperature is sufficiently low that water can be present in liquid state.

It has now been found that the corrosion in gas-distillate wells is due largely to the presence of small but appreciable amounts of low boiling organic acids, such as formic acid, acetic acid, propionic acid, etc., which are carried along by the hydrocarbon flow. These acids are present in the water which condenses from or is entrained by the hydrocarbon stream, and during the course of prolonged operation of the well are capable of causing extremely severe corrosion of the well tubing, fittings and flow lines. Other acidic constituents which are encountered in some gas producing wells and which likewise may be corrosive are phenolic compounds.

In some cases corrosion of well tubing may result from the presence of inorganic salts such as the sulfates or chlorides of magnesium, calcium

2

and iron. These materials in the presence of water and under elevated temperatures as encountered in wells may undergo hydrolysis to form the corresponding inorganic acids which are capable of attacking well tubing. In other cases hydrogen sulfide dissolved in water carried by the hydrocarbon stream may be effective to promote corrosion of metal parts.

The present invention is directed to overcoming corrosion problems of the above indicated type and provides a method of preventing or mitigating such corrosion. According to the invention, an ion exchange material adapted to react with the corrosive constituent is introduced into the well and brought into contact with the hydrocarbon flow stream to remove the corrosive constituent therefrom by ion exchange reaction before it has had the opportunity to attack the well tubing appreciably. Either an anion exchange material or a cation exchanger, or both, may be employed dependent upon what the particular constituent is that is apt to cause the corrosion. For example, in gas-distillate wells where the relatively low boiling organic acids are the cause, an anion exchange material capable of replacing the acid anion by an hydroxyl ion may be used. Anion exchangers suitable for this purpose are well known and include resins such as amine-formaldehyde, basic dyestuff such as aniline black, natural inorganic adsorbents such as hydroxyapatite and dolomite and synthetic heavy-metal silicates. Such exchangers may also be employed where aqueous hydrogen sulfide or phenol is the cause of corrosion.

On the other hand, in cases where the corrosion results from the presence of hydrolyzable inorganic salts of magnesium, calcium or iron in the water carried by the flow stream, a cation exchanger may be used which is capable of removing the magnesium, calcium or iron cation and replacing it by an alkali metal ion such as sodium. Known exchangers of this type are the zeolites which include processed green sand and synthetic gel zeolite. Alternatively, the hydrolyzable salts may, if desired, be removed by contacting the flow stream first with a cation exchanger capable of substituting the hydrogen ion for the metallic cation and immediately thereafter with an anion exchanger to remove the resulting inorganic acid. Cation exchangers suitable as the first contact material include resins such as tannin-formaldehyde and phenol-formaldehyde, certain phenolic sulfonic acid derivatives and sulfonated carbonaceous materials such as coal, lignite and peat.

The accompanying drawing, which illustrates a mode of carrying out the invention, is a dia-grammatic vertical sectional view of the lower portion of an oil well.

In the drawing, 10 represents a lower portion of the well casing which extends down through the productive formation 11 into the formation therebeneath, the end of the casing there being sealed off by means of cement plug 12. The casing has perforations 13 opposite the productive formation 11. Well tubing 14 is positioned within the casing and the upper annular space between the tubing and casing is sealed off by means of packer 15. The lower portion of the tubing 14 extending below the packer 15 has perforations 20 to permit the flow of fluids from the productive formation into the tubing and the end of the tubing is closed as shown at 16. A container 17 made of perforated sheet metal or plastic material or of heavy wire screen is positioned within the well tubing 14 and contains an ion exchange material adapted to remove the corrosive constituent from the flow stream. The upper portion of container 17 is designed so that the container may be lowered into or withdrawn from the tubing on a conventional wire line and is provided with a locking device 19 which may be of any known or suitable type for securing the container in place within the tubing.

With the arrangement as shown, the hydrocarbon stream flows from the productive zone 11 through casing perforations 13 and into the tubing through perforations 20, thence into the container 17 wherein the flow stream comes in intimate contact with the ion exchange material or adsorbent 18, whereby the corrosive constituent is removed by ion exchange reaction. After the adsorbent has been used for sufficient time to become saturated and lose its effectiveness for further removal of the corrosive constituent, it may be regenerated in situ by shutting off the well flow, injecting into the tubing a regenerating solution and permitting the solution to contact the adsorbent. Where the adsorbent is an anion exchanger, a solution of suitable alkali, such as sodium carbonate or caustic soda, may be used as the regenerating agent. In the case of cation exchangers regeneration may be effected by an acid solution. Also, if desired, the container 17 may be periodically removed from the well and the used adsorbent replaced by fresh material.

It will be understood that the above described embodiment is merely illustrative of one means of practicing the invention and that many modifications may be made within the scope of the invention. For example, in dually completed wells wherein the well is permitted to produce from one horizon through the tubing while also producing from another horizon through the annular space between tubing and casing, corrosion within the tubing may be mitigated in the manner above described while corrosion of the outer surface of the tubing and inner surface of the casing may be prevented by suitably positioning a batch of the ion exchange adsorbent in the

annular space to contact the hydrocarbon flow therein. Again, in cases where corrosion is apt to occur only in the upper part of the well, it may be desirable to place the adsorbent at an upper level in the well rather than near the bottom of the tubing. For example, in high pressure gas-distillate wells it has been observed that most of the corrosion occurs at depths above 3000 feet; evidently because it is only within this shallower zone that the temperature is sufficiently low that water carried by the hydrocarbon vapors can condense and form an aqueous organic acid phase. In such cases it may be desirable to place the ion exchange adsorbent near the lower edge of this zone where condensation first occurs.

What I claim and desire to protect by Letters Patent is:

1. In the production of petroleum hydrocarbons through a well wherein the hydrocarbon flow stream contains a constituent tending to cause corrosion of the well tubing, the method of mitigating such corrosion which comprises placing within the well a granular mass of ion exchange material adapted to remove the corrosive con-

stituent from the hydrocarbon stream by ion exchange reaction, and bringing the hydrocarbon stream in contact with the ion exchange material to remove said constituent.

2. In the production of petroleum hydrocar-

bons through a gas-distillate well wherein the hydrocarbon flow stream contains low boiling organic acids which tend to cause corrosion of the well tubing, the method of mitigating such corrosion which comprises placing within the well a granular mass of anion exchange material adapted to react by ion exchange with such organic acids, bringing the hydrocarbon stream in contact with the ion exchange material and thereby removing said organic acids.

3. In the production of petroleum hydrocarbons through a well wherein the hydrocarbon flow stream contains an inorganic salt capable of hydrolyzing to form an inorganic acid corrosive to the well tubing, the method of mitigating such

corrosion which comprises placing within the well a granular mass of cation exchange material adapted to exchange an alkali metal ion for the cation of said salt, and bringing the hydrocarbon stream in contact with the ion exchange

material to effect the ion exchange.
